(57) **CLAIM**

The ornamental design for a scooter, as shown and described.

DESCRIPTION

FIG. 1 is a front, right, and top perspective view of a scooter, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of a part of a handle in FIG. 1.

FIG. 10 is a partial enlarged view of an area comprising a wheel in FIG. 1; and,

FIG. 11 is another front, right, and top perspective view of the scooter, wherein the scooter is in a folded state.

The dash-dot broken lines represent the boundaries of the enlarged partial views of FIGS. 9 & 10. All other broken lines represent portions of the scooter that form no part of the claimed design. None of the broken lines form a part of the claim.
